Attorney

UNITED STATES PATENT OFFICE.

NEWTON C. GARDNER, OF CAIRO, ILLINOIS.

CHOKE ROD.

Application filed March 31, 1922. Serial No. 548,547.

To all whom it may concern:

Be it known that I, NEWTON C. GARDNER, a citizen of the United States, residing at Cairo, in the county of Alexander and 5 State of Illinois, have invented a new and useful Choke Rod, of which the following is a specification.

This invention relates to choke rods, the primary object of the invention being to 10 provide means for locking the choke rod in its active position to cut off, to a degree, the air supply entering the carburetor.

Another object of the invention is to provide a device of this character having means 15 to normally urge the rod to its inactive position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is a fragmental elevational view 30 of a choke rod constructed in accordance with the present invention, the rod housing being shown in section.

Figure 2 is a fragmental elevational view disclosing the rod in its active position.

Figure 3 is a sectional view taken on line 35 3—3 of Figure 2.

Figure 4 is an elevational view of the rod.

Referring to the drawing in detail, the reference character 5 designates the choke 40 rod which has connection with the usual choke valve that controls the air passing to the carburetor of an engine, not shown.

The rod 5 is formed with circumferential grooves 6 that are disposed in spaced relation with each other, as clearly shown by Figure 1 of the drawing, the spaces between predetermined grooves varying to insure an accurate adjustment of the choke rod 5, and permit the choke rod to be moved to a position to admit a quantity of air to the carburetor adapting the carburetor for use in various temperatures, eliminating the necessity of adjustment the carburetor for cold weather.

The lower end of the housing 7 is formed

with an inwardly extended flange 8 providing a rest for the washer 9 which cooperates with the washer 10 for supporting the split resilient ring member 11, which is preferably circular in cross section. 60

Secured at one end of the housing 7 is a cover plate 12 formed with openings, by means of which the device may be secured to the instrument board of a motor vehicle.

Supported on the rod 5, at a point adjacent to the outer end thereof is a coiled spring 13 which has its lower end contacting with the pin 14 carried by the rod 5, the opposite end of the coiled spring contacting with the cover plate 12, so that when the rod 5 is pulled through the housing, the spring is placed under tension to urge the choke rod 5 to its normal position, and at the same time retard movement of the rod 5 when the same is being moved to operate 70 the choke rod.

Secured to one end of the rod 5 is a button, indicated at 15, which may be gripped by the operator to move the rod 5 against the tension of the coiled spring to 80 operate the air valve of the carburetor not shown.

Thus it will be seen that if it is desired to secure the rod 5 in a predetermined position, it is only necessary to move the rod 85 against the tension of the coiled spring 13 until the same has assumed its proper position.

The rod 5 is now released, whereupon the ring member 11 moves into the groove adjacent thereto to lock the rod 5 against movement. It is obvious that if it is desired to move the rod 5 to its normal position, a slight pressure on the button 15 will expand the ring member 11 and permit the rod 5 to 95 move through the ring member.

Having thus described the invention, what is claimed as new is:—

In a device of the character described, a tubular housing, an inwardly extended 100 flange formed at one end of the housing, a washer supported within the housing and contacting with the flange member, a split resilient ring member positioned on the washer, a washer positioned on the split ring member and cooperating with the first mentioned washer to hold the spring ring member in position within the housing, a choke rod having notches formed in the periphery thereof, the notches being disposed in 105

spaced relation with each other, said ring member adapted to move into the notches of the rod to hold the rod in various positions of adjustment, a handle at one end of the rod and resilient means on the rod for restricting movement thereof.

In testimony that I claim the foregoing

as my own, I have hereto affixed my signature in the presence of two witnesses.

NEWTON C. GARDNER.

Witnesses:

ERNEST HARDMAN,
ROBT. A. HATCHER.
